UNITED STATES PATENT OFFICE.

AUGUST H. DEIKE, OF GUELPH, ONTARIO, CANADA.

WEIGHING-SCALE.

SPECIFICATION forming part of Letters Patent No. 392,995, dated November 20, 1888.

Application filed June 23, 1888. Serial No. 278,025. (No model.)

To all whom it may concern:

Be it known that I, AUGUST HERMAN DEIKE, cabinet-maker, of the city of Guelph, in the county of Wellington, in the Province 5 of Ontario, Canada, have invented a certain new and Improved Weighing-Scale, of which the following is a specification.

The object of the invention is to design a simply-constructed scale which will be sensitive in its operation; and it consists of a rolling trunnion carried on a stationary straight track and having curved wings extending from opposite sides of it, the outer circumference of each wing being equal in diameter 15 and shaped on a true circle which joins the circle of the trunnion, the weight being suspended from the trunnion by a flexible cord, or its equivalent, passing over one of the curved wings, and the weighing-tray similarly 20 suspended from the trunnion by a flexible cord, or its equivalent, carried over the other curved wing. An index-finger connected to the center of the trunnion and operating in conjunction with a properly-marked index-plate completes the essential portions of my 25 scale.

The drawing shows a perspective elevation of my improved scale.

A represents a straight track supported on 30 a light and gracefully-constructed frame, B.

C is a trunnion which rests on the track A, and is preferably grooved to fit onto the said track.

D is a curved wing extending from the trunnion C, the outer circumference of the wing D being shaped on a true circle which joins the circle of the trunnion, as indicated. E is 35 a similar curved wing extending from the opposite side of the trunnion C and equal in diameter to the wing D.

F is a piece of wire or other flexible material attached at one end to the trunnion C. This wire is carried loosely over the wing D, and has connected to its other end a weight, G.

H is a piece of wire or other flexible material similar to the wire F and connected to the trunnion C. This wire H is carried loosely over the wing E and has the weighing-tray I connected to it, as indicated. The wings D 45 and E are preferably grooved to receive their respective wires F and H. The weight G and should be made sufficiently heavy to counter-

balance the weighing-tray I and hold the point on the circumference of the wing D farthest from the center of the trunnion substantially 55 level with a horizontal line drawn through the center of the trunnion C.

In order to hold the trunnion C in its place on the track A, and to do so without interfering with the free rolling movement of the said 60 trunnion, I wrap round each end of the trunnion C a cord or other flexible material, J, and connect the ends of each cord J to a winding-key, K, situated at each end of the track A, as indicated. By winding the cords J on 65 the keys K at one end of the track and unwinding the said cords situated at the other end of the track the position of the trunnion C may be readily adjusted.

L is an index-finger connected to the center 70 of the trunnion C and extending across the face of the scale-plate M, which is properly marked to indicate the weight which may be placed on the tray I.

It will of course be understood that I do not 75 confine myself to the tray I, as any device by which the article to be weighed can be supported from the wing E will answer, and I wish any such device to be considered an equivalent for the tray.

When the article to be weighed is placed on the tray I, the wing E will be drawn down, and the wing D, from which the weight G is suspended, will move up, and consequently, owing to the positions of the wings relatively 85 to the trunnion C, the point from which the tray I is suspended will move nearer to the center of the trunnion C as the wing E is drawn down, while the point on the wing D from which the weight G is suspended will 90 move farther from the center of the trunnion C, and thus the power of the weight is increased in proportion to the weight of the article being weighed.

The scale-plate is properly marked to indicate the exact weight placed on the tray.

What I claim as my invention is—

1. A weighing-scale comprising a stationary straight track, a trunnion rolling on said track and having curved wings extending 100 from its opposite sides, the outer circumference of each wing being equal in diameter and shaped on a true circle joining the circle of the trunnion, flexible cords suspended from

the wings, a weight and a weighing-tray hanging from said cords, an index-finger connected to the trunnion, and a properly-marked scale-plate, over which the finger travels, substantially as and for the purpose specified.

2. A weighing-scale comprising a rolling trunnion, a stationary straight track on which the trunnion runs, keys at the ends of the track, cords connected to said keys and passing around the opposite ends of the trunnion, said rolling trunnion having curved wings extending from its opposite sides, the outer circumference of each wing being equal in di-

ameter and shaped on a true circle joining the circle of the trunnion, flexible cords carried by said wings, a weight and a weighing-tray suspended by said cords, an index-finger connected to the trunnion, and a properly-marked scale-plate, substantially as and for the purpose specified.

Toronto, April 27, 1888.

AUGUST H. DEIKE.

In presence of—

CHARLES C. BALDWIN,
CHAS. H. RICHES.
